CLAIM

The ornamental design for an elastic leg support, as shown and described.

DESCRIPTION

FIG. 1 is a perspective view of an elastic leg support showing my new design being pulled into position on a person's leg;

FIG. 2 is a top plan view thereof;

FIG. 3 is a bottom plan view thereof;

FIG. 4 is a left side view thereof;

FIG. 5 is a right side view thereof;

FIG. 6 is a front elevational view thereof; and,

FIG. 7 is a rear elevational view thereof.

The characteristic feature of the design resides in the generally U-shaped straps secured to the top edge of the leg support.

The portions shown in broken lines in FIG. 1 are for illustrative purposes only and form no part of the claimed design.
